UNITED STATES PATENT OFFICE.

MORNE NEREW, OF HAYDEN, ARIZONA, ASSIGNOR TO A. M. WERNER, OF HAYDEN, ARIZONA.

ELECTRICAL WATER-HEATING UNIT.

Application filed June 11, 1925, Serial No. 36,479. Renewed December 18, 1926.

My invention relates to electrical heating units particularly adapted, although not necessarily, for use in water heaters, and a purpose of my invention is the provision of an electrical water heating unit which is manually adjustable to control the flow of current through the unit, and which is automatically adjustable to compensate for the decrease in resistance as offered by the water between the electrodes of the unit as a result of the separation of the minerals contained in the water, and in such manner that the current flow between the electrodes after such manual adjustment has been made is maintained constant.

I will describe only one form of electrical water heating units embodying my invention and will then point out the novel features thereof in claims.

20 In the accompanying drawings—

Figure 1 is a view showing in vertical section and partly in elevation one form of electrical water heating unit embodying my invention in applied position with respect to the tank of the water heater.

Figure 2 is a vertical sectional view taken on the line 2—2 of Figure 1.

Referring specifically to the drawings in which similar reference characters refer to similar parts in each of the views, my invention in its present embodiment is shown as applied to the tank T of a water heater, the bottom wall 15 of such tank having secured to the under side thereof a plate 16 of insulated material. Extending upwardly through and rearwardly fitted in plate 16 is a reduced extension 17 of a bearing sleeve 18, a shaft 19 being rotatable in the sleeve with its opposite ends projecting from the sleeve. The upper end of the shaft 19 is provided with a pinion 20 which constantly meshes with a rack bar 21 slidable in a yoke 22 of the sleeve 18. The lower end of the shaft is provided with a knurled head 23 by which the shaft can be manually rotated to move the rack bar horizontally in one direction or the other. A bracket 24 is secured to one end of the rack bar 21 through screws 25, the bracket serving to support a carbon electrode 26 in upright position upon one end of the rack bar.

Extending upwardly through the plate 16 is a binding post 27 formed at its upper end with a head 28 to which is secured by means 55 of screws 29 the lower end of a thermostat

30, the latter being conventional in that it is made up of a plurality of strips of metal having different coefficients of expansion. Secured to the thermostat 30 is a carbon electrode 31 which is adapted to cooperate 60 within electrode 26 in providing a gap between which current is adapted to flow for heating the water in the tank.

Current is adapted to be supplied to the electrode 26 through the medium of a conductor 32 connected to a conducting cap 33 threaded on the lower end of the extension 17. It is to be noted that the construction of the cap 33 is such as to completely house the knurled nut 23 and to provide a water tight 70 joint between the plate 16 and the extension 17. As the sleeve 18 of the shaft 19 is formed of conducting material, current from the conductor 32 will flow upwardly through the conducting yoke 22 and from the latter 75 through a conductor 34 connected to the electrode 26. With the electrodes 26 and 31 immersed in the water in the tank, current will flow from the electrode 26 through the gap between the electrodes to the electrode 31 and from the latter downwardly through the thermostat and binding post to a conductor 35.

In practice, the gap between the electrodes can be manually varied by an adjustment of 85 the electrode 26 through manipulation of the shaft 19, and for the purpose of varying the amount of current flowing between the electrodes, it being understood that as the gap is increased the body of water between the 90 electrodes is correspondingly increased to increase the resistance and hence retard the flow of current between the electrodes. In this manner the rate of heating the water in the tank can be controlled at will. In order 95 to prevent the two electrodes from coming into actual contact with each other a head 36 of insulating material is carried by the electrode 26 so as to be interposed between the two electrodes, as clearly shown 100 in Figure 1.

After the desired adjustment of the electrode 26 has been effected, and current is supplied to such electrode, the water in the tank is heated by the flow of current between the electrodes, and with heating of the water the flow of current automatically increases due to the fact that the heating of the water separates the minerals therein thereby reducing its resistance to the flow of 110

current therethrough which as a consequence increases the flow of current beyond the flow as previously determined by the adjustment of the electrode 26. To compensate for this increased flow of current the thermostat 30 has been provided, and during the heating of the water the thermostat being exposed to the increased temperature will respond to such increase by a lateral flexing to move the electrode 31 away from the electrode 26 thereby increasing the gap between the two and of necessity increasing the resistance to the passage of current sufficiently to reduce the current to the normal rate of flow as previously determined by adjustment of the electrode 26.

From the foregoing description it will be manifest that after the heating unit has been once adjusted to effect a predetermined rate of flow of current between the electrodes that the reduced resistance as offered by the heated water would be ineffective to change such rate of flow so that the current flow is at all times constant.

Although I have herein shown and described only one form of electrical water heating unit embodying my invention, it is to be understood that various changes and modifications may be made therein without departing from the spirit of the invention and the spirit and scope of the appended claims.

What I claim is:

1. An electrical water heating unit comprising a pair of spaced electrodes, one supported for manual adjustment to vary the distance between the two, and a thermostat for supporting the other electrode in a manner to vary the distance between the two

electrodes in accordance with temperature changes.

2. An electrical water heating unit comprising a pair of spaced electrodes, slideable means for supporting one of the electrodes, rotatable means manually operable to actuate the slideable means to vary the distance between the electrodes, and a thermostat for supporting the other electrode in a manner to vary the distance between the two electrodes for the purpose described. 45

3. An electrical water heating unit comprising a bearing sleeve, a shaft rotatable in the sleeve, a rack bar supported for sliding movement on the sleeve, an operative connection between the rack bar and shaft whereby the rack bar is moved in one direction or the other according as the shaft is rotated in one direction or the other, an electrode carried by said bar, and a second electrode supported in spaced relation to the first electrode so that by an adjustment of the bar, the first electrode will be moved to increase or decrease the space between the two electrodes. 50

4. An electrical water heating unit as embodied in claim 3 wherein a thermostat supports the second electrode in the manner and for the purpose described. 60

5. An electrical water heating unit as embodied in claim 3 wherein said sleeve bearing is provided with a threaded extension, a plate of insulated material threaded on the extension, said shaft projecting through and beyond the extension and provided with a head, and a conducting yoke threaded on the extension and inclosing said head. 70 75
